UNITED STATES PATENT OFFICE.

JAMES H. REED, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

Application filed June 23, 1923. Serial No. 647,286.

This invention relates to a lock stitch shoe sewing machine of the type shown in my prior application for Letters Patent, Serial No. 542,666, filed March 10, 1922, of which this case is a division in part and with respect to subject matter common thereto. Said machine sews a lock stitch seam and has a straight hook needle and a shuttle for supplying a shuttle thread on the outer side of the sole of the shoe, while within the shoe there is a cooperating horn provided with an oscillating looper or whirl for supplying a cop or needle thread.

The present invention relates to the take-up devices which cooperate with the needle or cop thread in a machine of this type, and has for its object to provide mechanism whereby the needle loop, after being passed over the shuttle, will be drawn down upon the work and the stitch then tightened or set by drawing the thread locks into the material, said parts being adjustable to cause said thread locks to be drawn into the material to any desired point therein.

The foregoing and other objects of the invention, together with means whereby the same may be carried into effect, will best be understood from the following description of a preferred embodiment thereof illustrated in the accompanying drawings, in which:

Fig. 1 is a side elevation, partly broken away, of substantially the complete machine.

Fig. 2 is a front elevation on an enlarged scale of the instrumentalities located adjacent the stitch forming point.

Fig. 3 is a detail view illustrating the cooperation of the needle and whirl.

Fig. 4 is a detail plan view, and Figure 5 a detail front elevation, of the stitch forming takeup.

Fig. 6 is an enlarged sectional view of the work, showing the completed stitch.

The general organization of the machine and the cooperation of its several groups of mechanism will first be outlined, after which the construction and arrangement of that group to which the present case particularly relates will be described more in detail.

The main frame of the machine comprises a base 25 supporting a horn or work support 26 and from which rises an upright 27 carrying at its top the frame work 28 of the head. The horn 26 is of a size and shape to

render it capable of being inserted in the toe 55 of a shoe and comprises, as is usual in machines of this character, lower and upper portions, 26^a and 26^b, respectively, angularly disposed with respect to one another and rigidly connected by an intermediate elbow. 60 Said horn is mounted in a bearing 29 secured to the front of the base 25 at the top of the latter, being provided with a hollow base 52 having a journal portion 30 rotatably mounted in said bearing in such a manner as 65 to permit said horn to be turned as the sewing progresses. The work, which is designated as a whole by the letter A in Figures 1, 2 and 3, is shown more particularly in Figure 6 as comprising a McKay shoe having an upper p, an outsole q, and an insole r connected by stitches s. The needle 31, which is above the work, is straight and is formed adjacent its pointed lower end with an open, loop-engaging hook or barb. 70 Within the tip of the horn 26, and therefore below the work, or at the opposite side thereof from the needle 31, is a looper or whirl 32 which is rotatably mounted to oscillate in said horn, and is actuated, 75 through intergeared shafts 56 and 59 journaled respectively in the portions 26^b and 26^a of the horn, from a vertical shaft 62 extending co-axially through the journal portion 30 of the horn and rotatably mounted therein, said shaft being oscillated, 80 through a series of intermeshing pinions 65, by a reciprocating rack bar 67. The whirl 32 is provided with an eccentric thread opening 35 (Figure 3) to receive the cop or needle 85 thread 34, and with an axial opening 33 to receive the point of the needle when the latter descends to penetrate the work, whereby 90 said whirl operates to form a loop about the needle immediately above the hook of the latter, as indicated in Figure 3. Thereafter, as the needle rises, as shown in Figure 2, the loop so formed is drawn upwardly through the work. Above the work, or at the same side thereof as the needle, is an oscillating 95 discoidal shuttle 5 carrying a shuttle thread 6, said shuttle having a hook or beak 37, adapted when the needle rises, to engage the loop of the needle thread, remove it from the needle hook and pass it about the shuttle 100 and shuttle thread. Below the work support 26 is a main or stitch forming takeup 38 acting on the needle thread 34 and adapted to

draw the needle loop over the shuttle and down upon the work, thereby completing the formation of the stitch. Above the takeup 38, and within the horn 26, is a second takeup or stitch setter 39 adapted, after the formation of the stitch, to set the latter and draw the thread locks into the material. The needle thread 34 is held for the action of the takeup 38 and stitch setter 39 by a thread clamp 40, and is drawn from a suitable supply (not shown) in measured quantities for each stitch by a combined pull-off and thread measuring device 42, during which time the thread is held by a second thread clamp 401. The thread clamp 40 is located between the supply and the pull-off and the thread clamp 401 between the pull-off and the takeup. Between the thread clamp 401 and the takeup is a wax pot 41 through which the thread is guided in its passage from the former to the latter. During the formation and setting of each stitch, the work is clamped upon the horn 26 by a presser foot 43 carried by a presser foot bar 148, and between the formation of successive stitches said work is fed along the line of the seam by means of a feed point or awl 44, which serves also to perforate or incise the work to facilitate the passage of the needle therethrough. The pull-off 42 is operated by the rack bar 67 through a lever 142 having an adjustable slide 144 which is connected by a link 145 and lever 146 with the presser foot bar 148, whereby the stroke of said pull-off is automatically proportioned to the thickness of the work A. This mechanism as shown is substantially similar to that disclosed and claimed in my application, Serial No. 595,580, filed October 19, 1922.

The instrumentalities above referred to are all actuated from a main horizontal shaft 45 journaled in the head 28 and a vertical cam shaft 46 journaled in the upright 27 and operatively connected with the main shaft 45 by spiral gears 47. The main shaft 45 receives power from any suitable source through a pulley 48 loosely mounted on said shaft and adapted to be connected therewith by means of a clutch 49 operated, through suitable connections, by a treadle lever 50 at the base of the machine. If desired, the clutch 49 may have associated therewith a suitable stop mechanism adapted to stop the machine in a predetermined position. Such stop mechanism, being well known, is not shown in detail herein.

The foregoing explanation of the purpose, location and function of the several instrumentalities of the machine will be sufficient for a clear understanding of their cooperation with the takeup 38 and stitch setter 39 to which the present case relates and which will now be described in detail.

The takeup 38 comprises a roller carried

by a rod 108 suitably guided for longitudinal movement in a substantially horizontal plane in the base 25, said rod being connected at its rear end to a bell crank lever 109 fulcrumed upon the base 25 and carrying a cam roller 110 cooperating with a cam 111 on the shaft 46. The takeup roller 38 engages the needle thread 34 between two stationary guide rollers 112, said takeup roller 35 being movable between the rollers 112 in a direction transverse to the plane of the axes of said rollers, thereby deflecting said thread from its normal path and exerting a pull upon the same. As above stated, the takeup 38 is operated to pull the needle loop over the shuttle and down substantially to the work, the stitch setter 39 thereafter acting to set the stitch and pulling the thread locks *l* into the material to the desired extent, as shown in Figure 6. The throw or stitch setting pull of the stitch setter 39 is preferably constant in amount, and, in order to determine the depth to which the thread locks *l* are set in the material, means are preferably provided for adjusting or varying the effective action of the takeup 38 and thereby determining the condition of the stitch at the time of the operation of the stitch setter. To this end the guide rollers 112 are carried by slides 113 (see Figures 4 and 5) guided for movement toward and from the takeup roller 38 and toward and from each other in a bracket 114 secured to the front of the base 25. For simultaneously adjusting the slides 113 and guide rollers 112, there is preferably provided a vertical rod 115 journaled at its ends in the bracket 114, and having right and left threads engaging the slides 113 respectively, said rod having squared ends 116 whereby the same may be readily turned. The movement of the takeup 38 is a relatively slow and gradual one as compared to the quick stitch setting snap of the stitch setter 39.

Upon the completion of the stitch by the stitch forming devices and takeup, the stitch setter 39 acts to give the thread a short, sharp jerk, corresponding very closely to the snap given to the thread in hand sewing, and serving to set the locks of the stitches within the stock to an extent determined by the adjustment of the takeup, as above described. In order to accomplish this result in a satisfactory manner, it is desirable that the stitch setter engage the needle thread at a point as close as possible to the work, and to this end is located within the horn 26 above the bottom thereof. In the construction shown, said stitch setter comprises a roller adapted to engage the needle thread between guide rollers 90, which are located at the elbow of the horn, and deflect said thread out of its normal path between said rollers by a movement transverse to said path. To this end the roller 39 is carried by

a rod 117 guided for longitudinal movement in a bracket 260 secured within the lower portion 26^a of the horn, said rod being pivotally connected at its lower end to one end of a lever 118 located within the hollow base 52 and fulcrumed at its opposite end upon a fixed stud 119 therein. The lever 118 is connected intermediate its ends with the upper end of a vertical rod 121 guided for longitudinal movement in the journal portion 30 of the horn at one side of the shaft 62. The rod 121 is provided at its lower end with a notch 122 engaging the edge of a circular opening 123, concentric with the journal portion 30 and shaft 62, in a cross-head 124, whereby the operative connection of said parts is maintained, irrespective of the angular position into which the horn is turned. The cross-head 124 is provided with a stem 125 guided for vertical movement in the bearing 29 and formed with a recess which receives the end of a lever 126 fulcrumed upon the base 25 and having at its rear end a cam roller cooperating with a cam 127 on the shaft 46. The rod 121, cross-head 124, and lever 126 may, if desired, be substantially similar to the corresponding parts shown in my prior application, Serial No. 491,897, filed August 13, 1921. The stitch 30 setter 39 may be, and preferably is, given a movement to assist the takeup 38 in the formation of the stitch, thereby decreasing the necessary range of movement of the takeup. Such movement of the stitch setter, 35 if employed, is however, a relatively slow one, corresponding with the movement of the takeup, the stitch setting movement thereof being a relatively short and quick one as compared to that of the takeup, as above explained. It will be observed that the takeup

38 and stitch setter 39 are both in the form of rollers providing smooth surfaces over which the thread renders freely, as distinguished from thread gripping devices which have been found to injure the thread, the 45 thread in the present instance being held for the action of the takeup and stitch setting rollers by the main thread clamp 40, which engages the thread prior to its passage through the wax pot 41. 50

Having thus described my invention, I claim:

1. In a lock stitch sewing machine, a takeup comprising a pair of stationary thread guides, a thread engaging member between said thread guides and movable in a direction transverse to the line connecting said guides, said guides being relatively adjustable toward and from each other along the lines connecting said guides and transverse 60 to the direction of movement of the thread engaging member to vary the effective takeup action of said thread engaging member and a cam and connections for actuating said thread engaging member. 65

2. In a sewing machine, takeup mechanism comprising a pair of thread guiding rollers, a thread engaging roller located between said thread guiding rollers and movable in a direction transverse to the plane 70 of the axes of said thread guiding rollers, slides by which said thread guiding rollers are carried, said slides being guided for movement toward and from each other to vary the effective takeup action of said 75 thread engaging roller, and a screw for adjusting said slides simultaneously in opposite directions.

In testimony whereof I affix my signature.
JAMES H. REED.
